UNITED STATES PATENT OFFICE.

HATTIE L. FENNELL, OF KOCHVILLE, MICHIGAN.

DESIGN FOR A COOKING-STOVE.

SPECIFICATION forming part of Design No. 12,034, dated November 16, 1880.

Application filed July 16, 1880. Term of patent 7 years.

To all whom it may concern:

Be it known that I, HATTIE L. FENNELL, a citizen of the United States, resident at Kochville, in the county of Saginaw and State of Michigan, have invented certain new and useful Improvements in Designs for Cooking-Stove; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The invention consists in a design for stove-doors, &c., upon that class of stoves known as "farmers'" and "butchers'" stoves, and the design is fully illustrated in the accompanying drawings, in which—

Figure 1 is a front view, and Fig. 2 a side view.

The door A upon the front of the stove is

provided with an ornamental design of a farmer and his wife in working costume, and the side or oven doors are provided with an ornamental design of the farmer's child in sitting posture, with the representation of a toy in close proximity.

What I claim is—

1. The design for front stove-doors herein shown and described, consisting of the raised bust figures representing a farmer and his wife in working costume.

2. The design for side stove-doors herein shown and described, consisting of a raised figure representing a farmer's child in sitting posture with a fallen toy.

In testimony whereof I affix my signature in presence of two witnesses.

HATTIE L. FENNELL.
